CLAIM

The ornamental design for a mask as shown and described.

DESCRIPTION

The patent or application file contains at least one drawing executed in color. Copies of this patent or patent application publication with color drawing(s) will be provided by the Office upon request and payment of the necessary fee. FIG. 1 is a perspective view of a mask, showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof; and,

FIG. 7 is a bottom plan view thereof.

The dash-dash broken lines in the drawings show portions of the mask that form no part of the claimed design. The dot-dash broken lines in the drawings depict the boundaries of the claimed design, and only the portions of the mask within the boundaries form a part of the claimed design.
